[57] ABSTRACT

A clothes dryer so designed that a rotary drum will not start rotating even when a little child enters therein and closes an access door, unless a pushbutton type starting switch provided on the dryer is depressed externally.

SHEET 2 OF 2

FIG. 2

FIG. 3

CLOTHES DRYER

BACKGROUND OF THE INVENTION

1. Field of the Invention

This invention relates to a safety device of a clothes dryer of the type having a rotary drum.

2. Description of the Prior Art

Conventional clothes dryers of the type described have been provided with a safety device such as a door switch and designed such that the rotary drum do not rotate unless and until an access door of the dryer is closed.

However, the door switch only is insufficient to ensure the safety of the dryers. For instance, when little children enter the rotary drum and close the access door internally, the rotary drum starts rotating, possibly resulting in loss of the lives of the children. Therefore, safer clothes dryers have been desired recently which are designed such that the rotary drum will not start rotating even when a time switch is switched on and the access door is closed, unless and until a starting switch is depressed.

SUMMARY OF THE INVENTION

The present invention has been achieved to meet such desire and a first object of the invention is to provide a clothes dryer in which a capacitor motor is employed for driving the rotary drum so as to provide for the use of a relay of a simple construction for the self-holding of the starting switch.

A second object of the invention is to a clothes dryer of the character described above, in which the movable contact plate of the starting switch is carried on an attraction member magnetically operated by the relay coil, so that said movable contact plate and said attraction member may be directly depressed by a pushbutton, whereby a reliable circuit closing operation of the starting switch can be obtained and further the starting switch can be rendered very simple in construction and inexpensive as compared with the type in which the movable contact plate is indirectly depressed by the pushbutton.

A third object of the invention is to provide a clothes dryer of the character described above, in which the starting switch is assembled into a compact unitary piece so that it may be mounted on or demounted from the clothes dryer simply by inserting or removing it into or from a mounting hole formed in the cabinet of the clothes dryer.

BRIEF DESCRIPTION OF THE DRAWING

FIG. 1 is a partially broken away and partially sectional vertical cross sectional view of an embodiment of 55 the clothes dryer according to the present invention;

FIG. 2 is a partially sectional enlarged view showing the essential portion of the clothes dryer; and

FIG. 3 is an electrical connection diagram of the clothes dryer.

DESCRIPTION OF THE PREFERRED EMBODIMENT

A preferred embodiment of the present invention will be described hereunder with reference to the accompanying drawing. Referring to FIG. 1, a rotary drum 2 is rotatably mounted within an appearance

cabinet 1 for rotation about a horizontal axis. A capacitor motor 3 to drive the rotary drum 2 and an exhaust fan 4 is mounted on the bottom wall of the cabinet 1 by means of a bracket 23'. The front wall of the rotary drum 2 is formed with an access opening 5 for loading and unloading clothes and the access opening 5 is closed by a door 6 hingedly mounted on the cabinet 1. A door switch 7 is provided on the cabinet 1 adjacent the door 6 to be opened and closed in response to the opening and closing operation of said door. The front wall of the rotary drum 2 is formed therein with a number of apertures 8. A heater mounting plate 9 with an electric heater 10 mounted thereon is provided generally co-extensive with the apertures 8 formed in the front wall of the rotary drum 2. The electric heater 10 is electrically insulated from the mounting plate 9 by an insulator 11 mounted on said plate. The heater mounting plate 9 is formed with an inward flange 12 along the inner peripheral edge thereof which rotatably supports the front wall of the rotary drum 2 through a Teflon sheet 13 having a small coefficient of friction. The back wall of the rotary drum 2 is formed with a central opening and a screen filter 14 made of nylon of 15 the like is stretched over said opening. The filter 14 is covered by a filter cover 15 from the inside of the rotary drum 2, which is made of polypropylene or the like and held in position by an annular projection 2' formed along the inner peripheral edge of the opening in the 20 back wall of the rotary drum and engaging the outer peripheral portion of said filter cover. This filter cover 15 holds the filter 14 by embracing the peripheral edge thereof while being resiliently supported by the annular projection 2' and can be mounted and demounted easily. A flat belt 16 is engaged around a pulley 17 mounted on the driving shaft of the motor 3 and the outer peripheral surface of the rotary drum 2 to transmit the driving force of said motor to said rotary drum to rotate the latter. The belt 16 is held taut by an idle pulley 18. Further, a belt 19 is engaged around a pulley 20 mounted on the driving shaft of the motor 3 and a pulley 22 mounted on the shaft 21 of the exhaust fan 4 to transmit the driving force of said motor to said exhaust fan to drive the latter. The exhaust fan 4 is enclosed by a fan case 23. The fan case 23 is formed with a flange 24 on the suction side which extends inwardly of the dryer to rotatably support the back wall of the rotary drum 2 through a Teflon sheet 25 having a small 25 coefficient of friction. On the inner surface of the rotary drum 2 are provided a plurality of substantially semicylindrical baffle plates 26 each made of a plastic material such as polypropylene and formed with a number of apertures 27 in the rear portion thereof. These baffle plates 26 serve to assist in tumbling and free fall of the articles to be dried within the rotary drum 2. The cabinet 1 is formed at the lower portion of the back wall thereof with an inlet opening 28 in register with the motor 3. The cabinet 1 is provided with 30 universal wheels 29 at the bottom thereof. The rotary drum 2 also has opening 30 formed in the front wall thereof in register with the respective baffle plates 26. A thermostat 31 is provided on the fan case 23 to detect the exhaust temperature. Another thermostat 32 is provided on the heater mounting plate 9 for the prevention of overheating of the rotary drum 2. The fan case 23 is formed with an exhaust opening 33. A time 35 40 45 50 55 60 65

switch 34 is mounted on the upper portion of the front wall of the cabinet 1, which opens and closes the contacts in the motor circuit and the heater circuit according to a preset timing as shown in FIG. 3.

A starting switch 35 is mounted on the cabinet 1 above the time switch 34 and the construction thereof will be described hereunder with reference to FIG. 2. The starting switch 35 comprises a relay coil 36 having two terminals 36', a substantially U-shaped retainer frame 37 on the rear wall portion 37' of which said relay coil 36 is mounted through a bracket 38 by means of a screw 39 or the like, a fixed contact plate 40 secured to the upper wall portion of said bracket 38 through an insulation plate 41 by means of a screw 40' or the like and having a fixed contact 42 thereon, a movable contact plate 43 arranged in opposed relation to said fixed contact plate 40 and carried on an attraction member 45 through an insulation plate 44, a tension spring 46 having one end anchored to said bracket 38 and the other end to the lower end of said attraction member 45 to bias said attraction member into a position spaced from said relay coil 36, said movable contact plate 43 and said attraction member 45 and said insulation plate 44 being tightened together by means of screws 47, a pushbutton 48 arranged in opposed relation to said movable contact plate 43 and made of an insulating material, said pushbutton 48 having a cylindrical portion 48' which is supported by a frame member 51 extending from the bottom wall portion 49 to the upper portion 50 of the front wall portion 52 of said U-shaped retainer frame 37 and a button portion 48'' which is projecting forwardly outwardly from said front wall portion 52 of said U-shaped retainer frame 37 and the front wall of the cabinet 1, and a spring 55 mounted around the cylindrical portion 48' of said pushbutton 48 to hold said pushbutton 48 in a position spaced from the movable contact plate 43.

Now, the electric circuit of the clothes dryer will be described with reference to FIG. 3. The starting switch 35 is provided between a power source 56 and the time switch 34 and connected in series with the door switch 7 and said time switch 34. The door switch 7 is also connected in series with the time switch 34. Further, the relay coil 36 of the starting switch 35 is connected between points A and B at which an electrical load is imposed. Reference numeral 57 designates a capacitor for driving the motor 3 and 58 designates a timer motor for driving the time switch 34.

The clothes dryer constructed as described above will operate in the following manner: Namely, first of all, articles to be dried are loaded in the rotary drum 2 and the time switch 34 is rotated into an "ON" position. Then, the door 6 is closed, whereupon the door switch 7 is placed in an "ON" position. However, the clothes dryer does not yet operate in this state. Then, the pushbutton 48 of the starting switch is depressed in the direction of the arrow C shown in FIG. 2 against the biasing force of the spring 55. Thus, the movable contact plate 43 is brought into contact with the fixed contact plate 40 and at the same time, the attraction member 45 is attached to the relay coil 36, whereby said relay coil 36 is energized. By the energization of the relay coil 36, the rotary drum 2 rotates at the rate of about 50 revolutions per minute and the exhaust fan 4 at the rate of about 2,000 revolutions per minute. The

electric heater 10 is also energized upon contact of the movable contact plate 43 with the fixed contact plate 40. Since the movable contact plate 43 is held in its closed position by the energized relay coil 36, the clothes dryer continues its operation even after the pressure is released from the pushbutton 48.

Therefore, the external air enters the cabinet 1 from the air inlet opening 28 formed at the lower portion of the back wall of the cabinet 1 rearwardly of the motor 3, passes around the motor 3 while cooling said motor and flows toward the heater mounting plate 9 as indicated by the arrows shown in FIG. 1. The air flows further into the spacing between the heater mounting plate 9 and the rotary drum 2 and thence into the rotary drum 2 through the apertures 8 formed in the front wall of the rotary drum 2 and the opening 30 communicating with the interior of the respective baffle plates 26, after being heated by the electric heater 10. Since each baffle plate 26 is formed with the apertures 27 at only the rear portion thereof, the heated air entering the rotary drum 2 from said apertures 27 and the apertures 8 in the front wall of said rotary drum flows everywhere within said rotary drum. The hot air emerging from the rotary drum 2 is cleared of fibrous dusts during passage through the filter cover 15 and the filter 14, and the humid hot air only is exhausted to the outside of the cabinet 1 through the exhaust opening 33.

When the door 6 is opened or the time switch 34 is turned off during the drying operation, the dryer stops its operation. For re-starting the dryer, the time switch 34 is rotated once again into its "ON" position and the door 6 is closed, and then the starting switch 35 is depressed. Even if the two thermostats 31, 32 are actuated and the contacts thereof are opened during the drying operation, the drying operation will not be interrupted because the circuit including these thermostats and the circuit of the relay coil 36 are connected in parallel with each other.

We claim:

1. A clothes dryer comprising an appearance cabinet, a rotary drum rotatably mounted within said cabinet for rotation about a horizontal axis, a capacitor motor for driving said rotary drum, an access opening formed in the front wall of said rotary drum for loading and unloading clothes, a door openably mounted on said cabinet for closing said access opening, a door switch operated in response to the opening and closing operations of said door, a time switch connected in series with said door switch and a starting switch connected in series with said time switch and said door switch, said starting switch consisting of a self-holding switch including a relay, a movable contact plate, and a pushbutton arranged in opposed relation to the movable contact plate of said starting switch.

2. A clothes dryer as defined in claim 1, wherein said starting switch is provided between a power source and said time switch and its movable contact plate is directly carried on a member adapted to be magnetically attracted by the relay coil so that said movable contact plate and said member may be depressed directly by said pushbutton.

3. A clothes dryer as defined in claim 2, wherein said starting switch includes a substantially U-shaped retainer frame secured to the cabinet, and said relay coil, said member, the movable and fixed contact plates

of said starting switch and said pushbutton are integrally mounted on said retainer frame in the form of a unitary piece of assembly, said U-shaped retainer frame being secured to the cabinet at the front wall portion thereof with said pushbutton projecting outwardly of 5 said cabinet.
